RODLESS PUMP

Walter N. Huff, Harwood, Tex.

Application September 24, 1936, Serial No. 102,423

5. Claims. (Cl. 103—44)

This invention relates to pumps, especially those used in oil wells and the object thereof is to produce a pump of simple construction, which is durable and efficient in operation.

5. One object of the invention is to eliminate the use of long lifting rods which in wells of great depth are a great disadvantage.

Another object of the invention is to use pressure generated by a pump at the surface or stored 10 in a pressure reservoir to compress a spring or air confined in an air-tight space within the well or both and use the energy of expansion thus stored in the spring in the air or in both to force the fluid above the surface. Other objects will 15 appear as the description proceeds.

The invention will be clearly understood from the following detailed description, taken in connection with the drawing, in which:

Figure 1 is a cross-section on a vertical diametrical plane.

20. Figure 2 is a cross-section looking in the direction of the arrows on line 2—2 of Figure 1.

Figure 3 is a cross-section looking in the direction of the arrows on line 3—3 of Figure 1.

25. The well tubing 1 reaches from the surface to a short distance above the bottom of the well. A cylinder 2, herein called the suction cylinder, is connected to said tubing by an annular collar 3.

The lower end of this suction cylinder 2 is 30 closed by means of an apertured plate 4.

A check valve 5 opening inwardly controls the aperture in the plate 4.

35. A removable device 6, designated in its entirety as a pumping device, is supported in the tubing on pins or projections 7, 7, secured to the walls of the tubing 1.

This device 6 comprises a cylinder 8 of greater diameter than the suction cylinder 2 having a closure cap 9 at its upper end and a hook 10 attached thereto by means of which the pumping device 6 may be lifted as a whole out of the tubing 1.

40. Within the cylinder 8 is a piston 11 having a stem 12 extending upwardly therefrom. A metal washer 13 is connected to the upper end of said stem or rests thereon. A coiled spring 14 is confined between said washer 13 and the closure cap 9. Supporting pins 15 or projections are secured on the walls 8 and when the coil spring 45 14 is extended the washer 13 rests upon the supports 15.

45. As the piston 11 is air-tight the air in the cylinder 8 above the piston is confined in that space and will be compressed on an upward movement of the spring.

Attached to the under side of the piston 11 is a rod 16 extending into the suction cylinder 2. To the lower end of rod 16 an apertured piston 17 is secured. A check valve opening upwardly and properly confined controls said aperture. 5

The well tubing 1 is closed at the top by an apertured cap 18. In the aperture of this cap a pipe 20 is suitably secured and leads to a valve casing 21 in which a three-way valve 22 operates.

10. From this casing lead two pipes, 23 communicating with the atmosphere and emptying into a tank for receiving oil from the well and 24 communicating with a pump or a reservoir under pressure and thus forming the source of pressure 15 for operating the pumping device. The arrangements for supplying the pressure to the well tubing and storing the delivered fluid may be of any preferred description but are preferably such as is shown in my co-pending application, Serial 20 No. 81,110, filed May 31, 1936.

25. The above description and the drawing illustrating the same are not to be considered as limiting applicant's device to the precise structure shown and described but rather as exemplary only.

30. In the operation of the device, valve 22 is turned to admit pressure into the well tubing 1, valve 18 closes and the space above the same is thus closed except for the inlet of the pressure fluid. Cylinder 8 while merely resting on supports 1 will remain in that position. Piston 11 receiving pressure on its lower face and being of greater area than piston 17 will rise, compressing the air above it and the spring 14. Piston 17 moving upward will force liquid from the upper portion of suction cylinder 2 into the well tubing and at the same time by its tendency to create a vacuum will draw fluid past check valve 5 into the suction cylinder 2. 35

40. On the release of pressure the coiled spring and the compressed air will force down pistons 11 and 17, valve 18 will open, valve 4 will close and therefore piston 17 merely moves down in the suction cylinder 2 without forcing the fluid in either direction. Piston 11, however, in its downward movement forces the fluid in the well tubing up around the exterior of cylinder 8 and, the outlet for the fluid having been opened in releasing the pressure, the fluid passes out 45 through the delivery pipe. The cycle is then 50 repeated.

Having thus fully described my invention what I claim is:

55. 1. In an apparatus for use in raising oil from

a well, a well tubing, a suction cylinder of smaller diameter than said well tubing, means forming a fluid tight connection between the upper end of said suction cylinder and the lower end of said well tubing, projections from the lower portion of said well tubing, and a pumping device positioned within the tubing, closed at its upper end and in communication with said tubing at its lower end removably supported by said projections, and extending into the suction cylinder whereby the pumping device as a whole may be removed from said well tubing.

2. The device as claimed in claim 1, wherein the pumping device comprises a pumping cylinder having a closed upper end and of greater cross-sectional area than that of the suction cylinder, an air-tight piston slidable in said pumping cylinder, an air-tight piston slidable in said suction cylinder and having an upwardly opening check valve therein, and a rod rigidly connecting said pistons and means for alternately applying and releasing pressure to the interior of said well tubing whereby on the application of pressure said pistons will rise and fluid above the suction cylinder piston will be lifted into the well tubing and the air in the pumping cylinder will be compressed and on release of pressure the compressed air will move said pistons down and lift to a higher level the fluid in the well tubing.

3. The device as claimed in claim 1, wherein the pumping device comprises a pumping cylinder having a closed upper end and of greater cross-sectional area than that of the suction cylinder, an air-tight piston slidable in said pumping cylinder, a stem extending from the upper face of said piston and a rigid washer on the upper portion of said stem, a coil spring bearing on said washer and on said closed upper end of said pumping cylinder, an air-tight piston slidable in said suction cylinder and having an upwardly opening check valve therein, and a rod rigidly connecting said pistons and means for

alternately applying and releasing pressure to the interior of said well tubing whereby on the application of pressure, said pistons will rise and fluid above the suction cylinder piston will be lifted into the well tubing and the air in the pumping cylinder and the coil spring will be compressed and on release of pressure the compressed air and spring will move said pistons down and lift to a higher level the fluid in the well tubing.

4. In an apparatus for use in raising oil from a well, a well tubing, a suction cylinder of smaller diameter than said well tubing, means forming a fluid tight connection between the upper end of said suction cylinder and the lower end of said well tubing, means for supporting said pumping device in said well tubing, said pumping device comprising a pumping cylinder, having a closed upper end and of greater cross-sectional area than that of the suction cylinder, an air-tight piston slidable in said pumping cylinder, a stem extending from the upper face of said piston and a rigid washer on the upper portion of said stem, a coil spring bearing on said washer and on said closed upper end of said pumping cylinder, an air-tight piston slidable in said suction cylinder and having an upwardly opening check valve therein, and a rod rigidly connecting said pistons and means for alternately applying and releasing pressure to the interior of said well tubing whereby on the application of pressure, said pistons will rise and fluid above the suction cylinder piston will be lifted into the well tubing and the coil spring will be compressed and on release of pressure the compressed spring will move said pistons down and lift to a higher level the fluid in the well tubing.

5. The device as claimed in claim 4 in which an apertured plate closes the lower end of the suction cylinder and there is an upwardly opening check valve controlling the aperture.
